FLUORESCENT TUBE CIRCUIT TESTER

John B. Cottell and Herman S. Starbuck, Cincinnati, Ohio, assignors to Continental Electric Equipment Co., Ludlow, Ky., a corporation of Ohio

Application January 12, 1950, Serial No. 7,178

Term of patent 14 years

(Cl. D26—1)

To all whom it may concern:

Be it known that we, John B. Cottell and Herman S. Starbuck, citizens of the United States, both residing at Cincinnati, in the county of Hamilton and State of Ohio, have invented a new, original, and ornamental Design for a Fluorescent Tube Circuit Tester, of which the following is a specification, reference being had to the accompanying drawing, forming part hereof.

Fig. 1 is a perspective view of the fluorescent tube circuit tester showing our new design, it being understood that the opposite side is a substantial duplicate of the side illustrated.

Fig. 2 is a top plan view of the device of Fig. 1.

Fig. 3 is a bottom plan view of the device of Fig. 1.

Fig. 4 is a vertical section on line 4—4 of Fig. 2 of the upper portion of the device of Fig. 1.

We claim:

The ornamental design for a fluorescent tube circuit tester, as shown and described.

JOHN B. COTTELL.
HERMAN S. STARBUCK.
